UNITED STATES PATENT OFFICE

ANDERTON BENTLEY, OF TOLEDO, OHIO.

ADJUSTABLE MOLD FOR REINFORCED CONCRETE CONSTRUCTIONS.

SPECIFICATION forming part of Letters Patent No. 772,398, dated October 18, 1904.

Application filed August 4, 1904. Serial No. 219,412. (No model.)

To all whom it may concern:

Be it known that I, ANDERTON BENTLEY, a citizen of the United States, and a resident of Toledo, in the county of Lucas and State of Ohio, have invented certain new and useful Improvements in Adjustable Molds for Reinforced Concrete Constructions; and I do hereby declare the following to be a full, clear, and exact description of the invention, such as will 5 enable others skilled in the art to which it appertains to make and use the same, reference being had to the accompanying drawings, and to the letters of reference marked thereon, which form a part of this specification.

15 My invention relates especially to improvements in the molds used in reinforcing concrete construction for the formation and uniting of beams, columns, and brackets.

The object of my invention is to provide a 20 mold for the formation of concrete structures, whereby the connected beams, columns, brackets, &c., of such structures may be formed into a single integral or united mass, thus avoiding the weak points incident to structures 25 of this class occasioned by joints and cracks at the connections of such columns, beams, and brackets.

Further objects of my invention are to provide a mold of this class that is simple and 30 cheap in its construction, easily adjustable for the formation of columns and beams of different sizes and lengths, readily knocked down after a formed beam or column has hardened, and capable of repeated use for the same class 35 of work.

The invention is fully described in the following specification and shown in the accompanying drawings, in which—

Figure 1 is a vertical elevation of a portion 40 of a column-mold and associated beam-molds with one of the beam-molds in longitudinal vertical section and the column-mold partly broken away. Fig. 2 is a top plan view of a square column and diverging beams. Fig. 3 45 is a similar view of an octagon column and diverging beams. Fig. 4 is a longitudinal vertical section of a portion of a beam-mold; and Fig. 5 is a cross-section of a beam, taken on the dotted lines $\alpha\alpha$ in Figs. 1 and 3 and 50 looking in the direction of the arrow.

Referring to the drawings. A represents a column-mold, which may be of square, octagon, or other desired shape, and B the connecting beam-molds, which are shown in the drawings as radiating from three sides of the 55 column-mold. The columns A when in square form comprise the corner or right-angled pieces a , of wood or other suitable material, which are of sufficient strength to withstand the weight of the concrete mixture when 60 poured therein. The inner edges of the angle-pieces a are rabbeted, as shown at b , for receiving the ends of the transversely-positioned boards or strips c , which latter are nailed or otherwise suitably secured thereto and complete the square. These boards are continued to the top of the column on the sides where there are no radiating beams and on the sides where there are such beams to the point of connection thereof with the side of the column. 65 The corner-pieces a and connecting boards or strips c of a column are retained together in rigid position by means of the angle-irons d and connecting locking-strips e , which latter are provided with a series of 70 bolt-receiving apertures e' to enable the same to be adjusted to the size of the perimeter of 75 a column.

The beam-molds B are composed of three 80 separable parts—that is, the two side pieces f and the bottom or floor piece g , which connects the two side pieces when in set-up position. The side pieces f are provided with a plurality of transverse strips h , which secure together the several boards composing 85 a side piece f and also act as bracing-strips for the molds when in set-up position. These strips h project below the plane of the bottom g of a mold and have their lower ends held in rigid spaced position with relation to a transversely-alining strip of the opposite side piece by means of the inserted braces i , which are tacked or otherwise secured thereto in a manner easy of removal and their upper ends held in parallel position by means of the 90 bolts j , which pass through said strips immediately below the plane of the bottom board g of the mold and retain the side pieces rigidly against said bottom. The side pieces f 95 may either continue below the plane of the 100

bottom g to a depth equal to that of the strips h , as shown in Figs. 1 and 5, or terminate on a plane with said bottom, as shown in Fig. 4. The reason for bracing the sides f of a mold in the manner described is to make the upper part of the sides f rigid to avoid expansion as the heavy concrete is deposited therein and at the same time to form a mold having the trough thereof unimpeded by bolts or lateral braces. The bottom g of a mold may be supported on the transverse bolts j , as shown, or on cleats formed on the sides f for that purpose.

When a beam-mold B is connected to a column-mold A, the end of the former is placed upon and supported by a transverse strip k , which has a portion embedded in the contiguous side of the corner-pieces a . The ends of the side pieces f of a beam-mold are continued to a plane with the inner edges of the connecting-boards of the adjacent corner-pieces a by means of extension-strips l , which are retained thereto in any suitable manner, and the space between said strips and the edge of the adjacent corner-board a filled by the insertion of a rabbeted piece m , which is secured to the side of the contiguous extension-strip.

It frequently happens that a beam-mold is not of sufficient length to span the distance between the two columns, in which case an extension l of a length equal to the intervening space is employed. As it is necessary in such cases to provide a support for the end of the beam-mold which terminates a distance from the column, I employ metal strips n , which are secured to the lower portion of the mold and pass around the inner edges of the extension-strips l at an angle adapted to best support the load.

In order to prevent an inward movement of a beam-mold with respect to a connected column-mold previous to the depositing of concrete within the latter, a longitudinal strip m' is secured to either side of the beam-mold in alining position with the edge of the associated corner-piece a of the column-mold and a wedge l' driven between the end of the strip m' and the edge of the corner-piece a , as shown in Figs. 1 and 2. It will thus be seen that the interlocking of the rabbeted portions of the corner-pieces a and the insertion-strips m prevents an outward movement of the beam-mold, while the strips m' and interposed wedges l' prevent an inward movement thereof.

Should it be desired to form a concrete bracket integral with the column and connecting-beam for aiding in the support of the beam, the end of the bottom g of a beam-mold is cut off a desired distance from the connecting-column and a board o inserted at the desired slant (usually forty-five degrees) between the severed end of the bottom g and the supporting-strip k . The sides f are retained

against the board o by means of the angled braces p , which are retained in position by means of a bolt j , which passes under the bottom board g at a point adjacent to the slanting piece o , the said braces also serving to prevent the spreading of the upper and lower portions of the sides f , as shown in Figs. 1 and 2, the lateral pressure of the load within the slanted portion being neutralized by a similar pressure thereof on the sides of the mold above the retaining-bolt.

The octagon columns are substantially the same in construction as the square ones except that a straight piece d' is employed in place of the right-angled pieces a . The edges of the pieces d' are either rabbeted to receive the transverse strips c' or the space is made narrow, as desired, by the use of insertion-strips, which are in turn rabbeted to receive the filling-boards, as shown. The adjusting-bands q (shown in Fig. 3) are made to accommodate themselves to the octagon shape of the column and may either be made of wood or metal.

It will be apparent from the above description that the beam and column molds are constructed so that they can be extended in length or enlarged in size, as desired.

In practice the boards c of a column are built up as the filling-in process progresses, thus enabling the work to be inspected as the concrete is deposited within a mold to ascertain whether or not it is being properly packed. When a beam and column have been completed and the concrete thoroughly dried, the beam-molds are easily removed by knocking the supporting-strips k from the columns and the braces i out from between the lower ends of the strips h after first loosening the bolts j , thereby allowing the sides f and bottom g to free themselves and drop down from a beam. The column-molds are removed by loosening the surrounding tightening-bands, thereby allowing the corner-pieces to drop away from the column and permitting the boards c to be removed.

It is obvious that such changes in the shape, form, proportions, and minor details of construction of the parts as fairly fall within the scope of my invention may be made without departing from the spirit or sacrificing any of the advantages thereof.

Having thus described my invention, what I claim as new, and desire to secure by Letters Patent, is—

1. A beam-mold comprising separable side and bottom sections, a plurality of strips secured to the side sections and projecting below the bottom section, braces between the ends of oppositely-disposed strips, and means immediately below and forming a rest for said bottom adapted to tighten said strips for the purpose described.

2. A mold for concrete construction, comprising a column-mold having vertical corner-

- pieces and connecting-strips, tightening-bands surrounding said column-mold, and a beam-mold removably attached to and communicating with the interior of said column-mold.
5. 3. A mold of the class described, comprising vertical corner members, removable strips connecting said members to form a column-mold, means for locking the column-mold against expansion, a trough communicating with a portion of the column-mold between the vertical members thereof, said trough comprising separable side and bottom sections, strips secured to the side sections and projecting below the plane of the bottom section, 10 bolts connecting the opposite strips, and braces interposed between the projecting ends of the connected strips for the purpose described.
4. A mold for concrete construction, comprising vertical corner members having rabbeted edges, boards connecting said rabbeted edges to form a column, a horizontal mold, strips secured to the sides of said mold in alining position and projecting below the same, braces separating said strips, means for contracting said strips, and means for removably connecting the end of said horizontal mold to a column between two corner-pieces thereof. 15
5. In combination, a column-mold comprising vertical corner members, connecting-strips, and tightening-bands, a beam-mold removably connected to the column-mold and communicating with the interior thereof and comprising side pieces, a bottom piece terminating at its connecting end in a downward slant, and means for preventing an expansion 20
- 25
- 30
- 35

of said side members when concrete is poured therein.

6. In combination, a column-mold comprising vertical corner-pieces, strips connecting the contiguous edges of said members and adjustable bands for surrounding said parts, beam-molds, extension means for connecting the ends of said beam-molds to the sides of said column-mold in communicating position, a slanting bottom in the beam-mold at the juncture-point of the latter with a column-mold for the purpose described. 40

7. A mold for concrete construction, comprising a column-mold and a beam-mold having removable connection with said column-mold, said beam-mold comprising separable side and bottom pieces, means for retaining said parts together and preventing expansion of the sides, and means for locking said beam-mold against independent longitudinal movement with respect to the column-mold. 50

8. In a mold of the class described a vertical receptacle, one or more horizontal receptacles communicating with the interior of said vertical receptacle, means for removably connecting said receptacles, and means for preventing independent movement thereof, substantially as described. 60

In testimony whereof I have hereunto signed my name to this specification in the presence of two subscribing witnesses. 65
